METAL BAR

Filed Dec. 7, 1921

Attorneys

UNITED STATES PATENT OFFICE.

WILLIAM BARNUM COWLES, OF CLEVELAND HEIGHTS, OHIO, ASSIGNOR TO THE WELDLESS CHAIN CORPORATION, OF CLEVELAND, OHIO, A CORPORATION OF DELAWARE.

METAL BAR.

Application filed December 7, 1921. Serial No. 520,544.

To all whom it may concern:

Be it known that I, WILLIAM BARNUM COWLES, a citizen of the United States, residing at Cleveland Heights, in the county 5 of Cuyahoga and State of Ohio, have invented a certain new and useful Improvement in Metal Bars, of which the following is a full, clear, and exact description, reference being had to the accompanying drawings.

This invention relates to a metal bar having a special cross section and which, while capable of other uses, has particular reference to a bar which shall greatly facilitate 15 the manufacture of weldless chain.

In my copending application Serial No. 245,057 filed July 15, 1918, I disclosed a die roll machine for rolling weldless chain from a single homogeneous bar of cruciform cross 20 section. In roll forging a weldless chain directly from a bar of this character I find certain disadvantages are incurred, namely, a bar of this shape cannot be heated uniformly and efficiently; the die rolls are subjected to undue work and strains; and lastly 25 there is considerable waste incurred due to the large extrusions from the die rolls.

With a bar of cruciform cross section, it will be obvious that the central portion 30 thereof contains more metal than each of the longitudinal ribs or fins which project radially therefrom. This being the case, if the bar is heated so that the longitudinal ribs or fins are brought to the desired temperature, then the central portion containing 35 the greater mass of metal will not have reached an equal temperature and hence undue work is imposed on the die rolls in shaping this underheated central portion. 40 If, on the other hand, the bar is heated until the central portion thereof is brought to the desired temperature, then the radially disposed fins or ribs have necessarily reached a higher temperature and are apt 45 to be burned. In this instance also, a larger amount of fuel and a longer time is required for the heating.

Probably more important, however, is the fact, that with a bar of cruciform cross section, the die rolls must penetrate the large central portion to a greater depth and force the displaced metal into the matrices and extrude the excess. In other words, the central portion of a bar of this character 50 furnishes the material to fill the matrices

and form the extrusion and hence all of this work is imposed on the die rolls which causes rapid wear thereon.

It will also be apparent that the central portion of a bar of cruciform cross section 60 provides more material than necessary to fill the die roll matrices and hence considerable material is extruded as waste.

Some of the objects of the present invention are to provide a bar, the cross section 65 of which shall be of such shape as to require a minimum of work by the die rolls in forging a weldless chain and thereby prolong the life of the die rolls; to provide a bar of this character which shall have a substantial 70 cross section and hence permit rapid and uniform heating thereof; to provide a bar, whose volume per unit of length shall closely approach the volume of the chain bar formed therefrom and hence 75 not only require minimum work by the die rolls but also reduce the waste from extrusion to a minimum; to provide a bar of the aforesaid character which may be easily 80 roll forged from any stock whose cross section is either circular or polygonal; to provide a bar which is especially adapted for the production of weldless chains and which may be formed by die rolls of a substantial 85 nature capable of withstanding the work imposed thereupon; while further objects and advantages will appear as the description 90 proceeds.

In the accompanying drawing wherein I have shown an illustrative form of my invention, Fig. 1 is a cross section of a bar 90 shaped in accordance with my invention; Fig. 2 is a similar view enlarged, and also illustrating in dotted lines the cross section of the bar after it has passed through the 95 chain forming die rolls; Figs. 3 and 4 are respectively a fragmentary sectional view and a side elevation of a die roll for rolling a bar such as shown in Figs. 1 and 2; Fig. 5 is a cross section of a cruciform bar ordinarily used in the manufacture of weldless chain; Fig. 6 is a similar view enlarged and also showing in dotted lines the cross section 100 of the bar after it has passed through the chain forming rolls; and Figs. 7 and 8 are 105 respectively a fragmentary cross section and a side elevation of a die roll for forming the cruciform bar shown in Figs. 5 and 6.

In carrying out my invention, I provide four die rolls A each having a cross section 110

similar to that shown in Fig. 3. Each die roll is formed with a centrally disposed circumferential rib 10, a grooved portion 11 disposed on each side of said rib, and 5 beveled surfaces 12, 12 on the outer peripheral edges of said die rolls. These die rolls are positioned in a machine identical with that disclosed in my aforementioned copending application and when assembled 10 therein, these die rolls define an opening whose cross section is similar to that shown in Figs. 1 and 2. A bar of metal having either a circular or polygonal cross section is then heated to the desired degree and 15 passed through the machine and die rolls in the usual manner. The bar which is extruded will have a cross section similar to that shown in Figs. 1 and 2 and for convenience I term this a four-bulb-bar. This 20 bar is formed with four ribs or fins 14, each of which has a rounded outer contour and each rib or fin forms a reentrant angle with an adjacent rib, the apex of this angle being rounded as indicated at 15. A cross section 25 of the four-bulb-bar shows that each rib or fin 14 and the central portion 16 thereof have a substantially equal mass, and hence a bar of this type can be quickly and uniformly heated before it is passed through 30 suitable chain forming die rolls.

More important, however, is the fact that a bar of this cross section greatly reduces the work of the matrices on the chain forming die rolls, as it approaches more closely 35 in shape the cross section of the chain bar produced by said matrices of the chain forming die rolls. By referring to Fig. 2 it will be observed that when a bar of this type is passed through the chain forming die 40 rolls, the matrices on these die rolls must penetrate the central portion 16 at certain spaced points to a depth which closely approaches the longitudinal center of the bar. The actual depth penetrated in the central 45 portion of a four-bulb-bar by the die roll matrices is indicated by the distance X and the metal displaced serves to fill the matrices of the chain die roll and the excess is extruded as thin webs between the die rolls.

50 In Fig. 6 I have shown a cross section of the usual cruciform bar and indicated in dotted lines is the shape of the chain bar. In this instance the actual distance penetrated in the central portion 20 is indicated 55 by the distance Y. For purposes of comparison between the distances X and Y the enlarged cross sections of the four-bulb-bar and cruciform bar have been drawn to the same scale and it will be at once apparent 60 that the distance X is approximately 33% less than the distance Y. It will be obvious that the die matrices rolling a four-bulb chain-bar will not be subjected to nearly so much work and strain as in the case of a 65 cruciform bar. Also in the case of a four-

bulb bar, the penetrating portions of the die matrices will not be surrounded by so great a mass of heated metal as in the case of the cruciform bar. It might be further noted that a cleaner and more sharply defined chain bar can be produced when the die matrices do not penetrate so great a mass of metal. 70

In the case of the cruciform bar a larger mass of metal is displaced from the central 75 portion than in the case of the four-bulb-bar and hence the displaced metal in the cruciform bar will more than fill the die matrices and produce more waste in the form of extrusions than with the four-bulb- 80 bar.

From the foregoing description and drawing it will be apparent that a four-bulb-bar possesses decided advantages over a cruciform bar and greatly facilitates the manufacture of weldless chain, as a major portion 85 of the work of the chain forming die roll is performed by the preliminary die rolls which shape the (round or polygonal bar) material into a four-bulb-bar. 90

Having thus described my invention, what I claim is:

1. A bar of metal having a central portion and radially disposed ribs projecting therefrom, each of said ribs and the central 95 portion of said bar having substantially equal masses of metal.

2. A bar of metal having a central portion and radially disposed ribs projecting therefrom, each of said ribs having a rounded 100 outer portion and the sides of each of said ribs being convergent as they approach the central portion of said bar.

3. A bar of metal having a central portion and radially disposed ribs projecting 105 therefrom, each of said ribs having a rounded outer portion, the sides of each of said ribs being convergent as they approach said central portion, and each of said ribs and central portions having a substantially equal 110 mass of metal.

4. A bar of metal especially adapted for the formation of weldless chain and comprising a central portion and four radially and equally spaced ribs projecting therefrom, each of said ribs and said central portion having a substantially equal mass of metal. 115

5. A bar of metal especially adapted for the formation of weldless chain and comprising a central portion and four radially and equally spaced ribs projecting therefrom, the outer portion of each of said ribs having a greater diameter than the inner portion connecting said rib to the central 120 portion of the bar. 125

In testimony whereof, I hereunto affix my signature.

WILLIAM BARNUM COWLES.
